UNITED STATES PATENT OFFICE.

FREDERICK A. HART, OF NEW BRITAIN, CONNECTICUT, ASSIGNOR TO LANDERS, FRARY & CLARK, OF NEW BRITAIN, CONNECTICUT, A CORPORATION OF CONNECTICUT.

HOT-WATER BOTTLE AND THE LIKE.

Application filed May 27, 1919. Serial No. 300,143.

To all whom it may concern:

Be it known that I, FREDERICK A. HART, a citizen of the United States, residing at New Britain, county of Hartford, and State 5 of Connecticut, have invented certain new and useful Improvements in Hot-Water Bottles and the like, fully described and represented in the following specification and the accompanying drawings, forming a part 10 of the same.

This invention relates to hot water bottles and the like, and particularly to hot water bottles made of metal.

It not infrequently happens in the use of 15 hot water bottles, that the bottle is sealed when only partially filled. As a result, when the hot water cools, there is created in the bottle a vacuum of considerable degree. Of- 20 tentimes this vacuum is so great as to cause an inward collapse of the metal body of the bottle. The vacuum at times is so great that even the use of a cross brace does not prevent collapse of the metal body due to the excess of atmospheric pressure.

25 It is the principal object of the present invention to provide a self-venting hot water bottle, that is to say, a bottle so constructed that upon any tendency toward the creation of a vacuum, there ensues an admission of 30 air to relieve such vacuum.

With this general object in view, the invention consists in the combinations, features, details of construction and arrangements of parts which will first be described 35 in connection with the accompanying drawing and then more particularly pointed out. In the drawing Figure 1 is a view in side elevation, with parts in vertical section, of a metal hot water bottle constructed in accordance with the invention.

40 Figure 2 is an enlarged view of the bottle taken in vertical section.

Figure 3 is a cross-sectional view taken on the line 3—3 of Figure 2, and

45 Figure 4 is a view similar to the upper portion of Fig. 2, showing a different position of the parts.

The bottle illustrated as an example 50 comprises a metal body 5 which may be of any desired shape and size. As shown, the bottle is proportioned to obtain a large volume of water with a flat or "watch" shape considered desirable for comfort and is flattened at the bottom so it can stand upright. The 55 body, in the present embodiment, is formed

with a neck 6 on which is mounted a threaded collar 7. This collar 7 may be forced onto the neck 6 and the rim of the neck spun solidly over the top of the collar, as clearly shown in Fig. 2. The bottle shown 60 in the present exemplification is closed during use by a cap or closure 8 which is threaded on the interior to screw onto the threaded collar 7 and which carries a sealing gasket 9. The exterior of the cap 8 65 may be knurled if desired, as illustrated in Fig. 1. In order to prevent loss of the cap and to provide means for carrying the bottle when hot, the cap may be attached to the collar 7 by a short link chain 10. 70

The invention includes means whereby a tendency toward the creation of a vacuum in the bottle permits the admission of air to relieve such vacuum. This may be accomplished, for example, by forming in the bot- 75 tle an air-inlet port and providing closure means for such port. Although variable within a wide range, in constructions embodying the invention to the best advan- 80 tage there is provided, in connection with an air-inlet passage, an abutment wall and a pressure-actuated member movable into and out sealing contact with the abutment wall, thereby to close and open the passage.

Although there may be a wide range in the 85 details of construction and arrangement of the elements mentioned, in the embodiment illustrated there is formed in the top of the cap, near the center thereof, an air-inlet port 11. The inner top wall 12 of the cap, which 90 comprises an abutment wall, is slightly con- 95 cave, and clamped between this part of the cap and gasket 9 is a flexible diaphragm 13 constructed of light rubber or other suitable material. It will be seen from the drawing, 100 that this diaphragm extends across the neck of the bottle when the cap is in place. To provide communication between the port 11 and the interior of the bottle, the diaphragm is provided with an aperture. In the present 105 instance, there is cut in the diaphragm a slit 14. This slit is so positioned that, regardless of the angular position of the diaphragm, it is always in alinement with the orifice of the gasket, and out of alinement with the port 11. 110 That is to say, the slit 14 is so positioned that when the diaphragm is pressed against the cap, the slit is offset from the port 11.

It will be seen that with the construction 115 described, there is a passage into the interior

of the bottle comprising port 11, the space between the cap and the diaphragm, and aperture 14.

In the use of the bottle above described, 5 any interior pressure, such as the surge of water, against the flexible diaphragm, causes the diaphragm to snugly nest against the abutment wall 12, as illustrated in Fig. 2. Since port 11 and aperture 14 are out of 10 alinement, this sealing contact of the diaphragm with the wall 12 effectively closes the passage mentioned. In other words, the port 11 is closed and no water can escape.

Should the cooling of the hot water in a 15 partially filled bottle tend to create a vacuum, the excess of atmospheric pressure against the diaphragm causes it to flex in the opposite direction, that is, away from the wall 12, to some such position as that shown 20 in Fig. 4. This movement of the diaphragm opens the port and passage and this permits the admission of air into the bottle to relieve the vacuum.

There is provided a tubular cross-brace for 25 the bottle having provision for the circulation of water, and held in place by beads formed in the bottle body.

Although capable of various constructions, 30 in the embodiment illustrated, there is provided a tubular cross-brace in the form of a cylindrical member 16, the ends of which abut against the side walls of the bottle body 5 as appears in Fig. 2. To permit circulation of water through the space enclosed 35 by the cross-brace, there is formed in the end edges of the member 16 a plurality of segmental openings 17. Furthermore, the member 16 is not a perfect cylinder but is provided with a narrow lengthwise slit 18. The 40 construction described permits the passage of water into and out of the tubular cross-brace.

To hold the brace in position, each side wall of the bottle body is formed with an

internal bead 19 of a circumference to embrace 45 the end of the tubular cross-brace. The two beads are located opposite each other and when the ends of the cross-brace are placed within the embrace of the beads, the brace is securely positioned without the 50 use of any extraneous fastening means.

The bottle herein illustrated is formed by welding together two similar parts and the cross-brace is assembled in the embrace of 55 the beads prior to the welding process.

With a metal hot water bottle such as that described, crushing by heavy weights is prevented by a cross-brace which does not interfere with circulation of water, and collapse of the metal body due to the creation of a 60 vacuum is prevented by provision for the admission of air by a construction which at the same time seals the bottle against escape of the water.

It is to be understood that the term "vacuum" 65 in the specification and claims is used in its relative, and not in an absolute, sense; and that the term "bottle" is used comprehensively.

What is claimed is:

A hot water bottle or the like, comprising 70 a body portion having a neck, a cap associated with said neck, a perforated gasket in said cap, the cap being provided with an air-inlet opening in its top, and a flexible 75 diaphragm mounted between the top of the cap and said gasket and having an opening in alinement with the opening of the gasket and offset from the opening in the cap, said diaphragm being movable into and out of 80 contact with the top of the cap, whereby air may enter the bottle under excess external pressure and egress of liquid from the bottle is prevented.

In testimony whereof, I have hereunto set 85 my hand.

FRED'K A. HART.
